United States Patent Office

Des. 221,193
Patented July 13, 1971

221,193

CASSETTE ALBUM

Oscar Goren, 2701 Grand Concourse,
Bronx, N.Y. 10468

Filed Apr. 8, 1970, Ser. No. 22,313

Term of patent 14 years

Int. Cl. D3—99

U.S. Cl. D87—1

FIG. 1

FIG. 2

FIG. 3

FIG. 1 is a top perspective view of a Cassette Album in closed position, showing my new design;

FIG. 2 is a top perspective view thereof in open position; and

FIG. 3 is a front elevational view thereof on an enlarged scale.

The bottom of the design is identical to that shown in FIG. 1.

I claim:

The ornamental design for a cassette album, as shown and described.
